MOTOR SUPPORT

Edward A. Freed, Moline, Ill.

Application May 24, 1940, Serial No. 336,901

3 Claims. (Cl. 248—20)

My present invention pertains in general to motor driven circulating air blowers of the type commonly used for supplying air for hot air heating and air conditioning systems, and is concerned particularly with a novel design of support for the motor or other driving means thereof.

In a blower of this kind the motor is usually mounted close to the blower housing to form a compact unit. The usual means of transmitting power from the motor to the blower wheel is through a belt drive. To ensure efficient operation of the blower it is necessary that the drive belt always be maintained at the proper tension so that slippage of the belt on the pulleys will not occur. The blower, operating at a predetermined R. P. M., produces a certain definite column of air output. To maintain a constant column of air output, the blower must be driven at a constant speed. If the speed of the blower is reduced because of slippage of the belt resulting from reduced tension thereon, the column of air output is decreased. It is therefore an object of my invention to provide a design of motor support which may be positioned close to the blower housing and which is self-adjustable to maintain the proper tension on the drive belt.

Another object of the invention is to so construct the motor support that an even driving tension will be exerted on the drive belt at all times without the need of adjusting the motor on the support.

A further object is to provide a resilient support for the motor to relieve it from danger of damage caused by shocks and jars.

A still further object is to construct an efficient and inexpensive design of motor support which is adapted to be used on the conventional type of air blower.

Additional objects, advantages and features of invention reside in the construction, arrangement and combination of parts involved in the embodiment of the invention as will appear from the following description and accompanying drawing, wherein—

Figure 1 is a side elevational view of a conventional air blower showing my improved motor support.

Figure 2 is a plan view of the structure shown in Figure 1 with a portion of the rear of the blower housing removed to show the motor support.

Figure 3 is an enlarged detail view of the motor support.

Figure 4 is an end view of the motor support 55

shown in Figure 3, but on an enlarged scale, and Figure 5 is an enlarged detail cross sectional view taken on the plane of line 5—5 of Figure 3.

The blower, referred to in its entirety by numeral 11, is of conventional design and includes a blower housing 12 which is supported in a frame 13. The frame 13 is formed of front and rear upright angle iron members 14 and 15 respectively disposed at each side of the housing 12. The lower ends of each pair of members 14 and 15 are secured to right and left hand horizontal angle iron base bars 16 and 17 respectively arranged in parallel relation directly below the bars 14 and 15. The upper portion of the bars 14 and 15 are riveted or otherwise secured to the adjacent sides of housing 12. A blower wheel (not shown) is rotatably mounted within the housing 12. The blower wheel is secured on a shaft 21 which is journaled in bearings 22 disposed at opposite sides of the housing 12. The bearings shown are of conventional design and are mounted on plate 23—one at each side of the housing—disposed below the shaft 21 and extending between the members 14 and 15. The ends of the plates 23 are supported on angle brackets 24 secured to the members 14 and 15.

A driving motor 26 is mounted at the rear of the housing 12 and at one side thereof on a motor support 27. A pulley 28 is provided on the motor 26 in the usual manner and is adapted to receive a drive belt 29. The belt 29 is also trained over a pulley 31 fixed on shaft 21.

The motor support 27 comprises a vertical end plate 41 secured to the rear end of base bar 16 and extends upwardly therefrom. A transverse brace member 42 is secured to the rear edge of plate 41 and extends across the frame 13 to a connection with base bar 17. A pair of plates 44, preferably formed of light gauge resilient material, are secured to the vertical end plate 41 and extend laterally therefrom. A motor base plate 45 is rigidly secured to the opposite end of the plates 44. The plates 44 are positioned one ahead of the other and at an angle relative to the vertical. The forward plate is disposed on a higher plane than the rear plate. This construction causes the motor base plate 45 to be disposed at a rearwardly and downwardly inclined angle. The angle of the plate 45 is preferably such that the face of the plate is in a plane parallel with a line drawn through the centers of pulley 28 and shaft 21. When the motor 26 is mounted on the inclined plate 45, the weight of the motor overhanging the motor support 27 tends to swing the plates 44 rearwardly and exert

a direct pull on the belt 29. This puts a tension on the drive belt 29 which aids in preventing the belt from slipping. By reason of this an idler or belt tightener pulley mechanism is not required. Further, because of the resiliency of the plates 44 the motor is relieved of shock and jars which might otherwise be imposed on it due to sudden starting and stopping of the motor with the load of the blower connected with it. From the foregoing description it will be seen that a motor support of this design provides the maximum of efficiency in operation, readily lends itself to a compact unit construction and is economical to manufacture.

While I have described, in connection with the accompanying drawing, the specific form in which I prefer to embody my invention, it is to be understood that the invention is not limited to the specific means which I have herein shown and described, and that, in fact, widely different means may be employed in the practice of the broader aspects of my invention.

What I claim, therefore, and desire to secure by Letters Patent is:

1. In a motor support, a vertical member, a pair of parallel resilient plates secured to said vertical member and extending laterally therefrom, said plates being positioned at an angle relative to the vertical and at different levels with respect to each other, and a motor base secured to the free ends of said plates and disposed in an inclined position.

2. In a motor support, a vertical member, a pair of parallel resilient plates secured to said vertical member and positioned at different levels, and a motor base secured to said plates.

3. In a motor support comprising a pair of resilient plates disposed in parallel angular planes and at different levels, and a motor base secured to said plates and positioned at right angles to said plates.

EDWARD A. FREED.
